(57) **CLAIM**

The ornamental design for a bench, as shown.

DESCRIPTION

FIG. 1 is a perspective view showing my new design; FIG. 2 is an enlarged partial perspective view of the area identified in FIG. 1;

FIG. 3 is a front view showing my new design;

FIG. 4 is a back view showing my new design;

FIG. 5 is a top view showing my new design; and

FIG. 6 is a bottom view showing my new design.

FIG. 7 is another perspective view thereof, but showing the bench seat lid in an opened position; and,

FIG. 8 is a cross-section perspective view taken along line 8-8 in FIGS. 3 and 5.

1 Claim, 8 Drawing Sheets
